OF NEW YORK

ELECTRIC SIGNAL BELL

Application filed December 14, 1926. Serial No. 154,845.

Plunger type electric vibrating bells, to which the present invention belongs and which are operable on alternating electric current circuits, are mainly favored on account of their economic current consumption. They have no open contacts and are used where inflammable gases or dust exclude the use of other types of electric signal bells or, at least, make the same less desirable.

10 The present invention, while primarily included in this class of electric translating devices, has for its particular object the construction and organization of parts, to produce a device of a high degree of efficiency and reliability of operation, in which the rate of vibration of the plunger or striker can be so adjusted that the acoustic effect of a bell, gong or other resonant body, though produced by the multiple strokes of the 15 plunger, is very similar to that of a single stroke bell and, therefore, fully adapted for code signaling, as now used in modern fire alarm telegraph systems.

The particular means bringing about this 20 peculiar actuation of the plunger include resilient means, in part carried by the armature of the electromagnet, and in part by the plunger itself, and cooperating with an adjustable stop, and are instrumental in adjusting the operation of the device to a high 25 degree of nicety.

The drawing shows in Fig. 1, a plan view, in Fig. 2, a vertical cross sectional view and, in part, an elevation of the device, and in 30 Fig. 3, a perspective view of the armature of the electromagnet.

A base or frame 10 carries an electromagnet 11, adapted to be energized by alternating current and having a, preferably, laminated core 12. The open pole ends of core 12 abut the front face of a pivoted armature 13, having cylindrical or other bearings 14 and, when magnet 11 is energized, attract armature 13. This armature is provided with 35 a blade spring 24, arranged substantially parallel to the front face of the armature, but preferably secured to the rear face thereof at or near the axis of movement and extending beyond the lower edge of armature 13. 40 Blade spring 24 contacts with the end of

plunger 25, upon which there is arranged a helical spring 26, one end of which bearing against a stationary guide tube 25' for and surrounding plunger 25, the other end bearing against a collar 26', forming part of and located near that end of plunger 25 which abuts blade springs 24. The opposite end of plunger 25 contacts with gong or resonant body 27 or operates any other translating device. 55

Armature 13 furthermore carries a second blade spring 28, secured to it at or near its axis of movement, but substantially at right angles to the face of armature 13 and extending rearward from its face where it is capable 60 of engagement with adjustable stop screw 29, provided on the frame of the device. This stop is mainly intended for regulating the movement of armature 13, by varying the distance between its front face and the pole 65 ends of core 12. This stop, when adjusted, also varies the relation between blade spring 24 and coiled spring 26 of plunger 25 and forces armature 13 more or less into the field 70 of attraction of magnet 11, for the purpose 75 of further influencing the rate of movement of armature 13 and the power of the stroke of plunger 25.

The bell operates as a vibratory bell in which the striker continues to strike the bell 80 as long as the circuit closer is closed, the latter being usually located at a remote point and may be a simple closing switch or the movable contact points operated by the code-wheel of a signal transmitter such as used in 85 fire alarm telegraphy or other similar signal transmitters.

When the circuit is closed, the armature is attracted and released by the magnet according to the cycle of alternation of the operating current and as long as the circuit is kept closed. The characteristic "chattering" of the armature in an alternating current magnet is, in the present invention, augmented by the springs 24 and 26 that at each attraction of the armature the resiliency of the full length of spring 24 is operative in resisting the attraction whereby spring 24 is bent and partially separated from armature 13, its resilience, therefore, greater, while at each re- 95 100

lease of armature 13, the resiliency of spring 24 is operative only along that portion of its length extending beyond the armature and, therefore, less. The vibrations of armature 13 and spring 24 having sufficient amplitude at the end of spring 24 to cause the striker 25 to effectively strike bell 27 at each alternation of current. This effect is clearly due to the location of spring 24 on the off side or rear face of armature 13.

It will be seen that when magnet 11 is energized and armature 13 is attracted that blade spring 28 separates from stop screw 29. Blade spring 24, contacting with plunger 25, compresses helical spring 26 and forces plunger 25 to strike gong 27. The elements controlling the movement of the reciprocating plunger 25 are, therefore, blade springs 24, 26 and 28. It is obvious that resilient means of other than blade shape may be employed in place of spring 28, such as helical wire or telescoping coils.

Though only spring 28 is directly engaged by stop screw 29, this single means is adapted to adjust the tension of the entire resilient system, comprising in this preferred form, all three springs 24, 26 and 28, and thereby controlling the efficiency of the whole signal device.

30 We claim:—

1. In combination, an electromagnet, an armature actuated thereby, a plunger, resilient means on said armature contacting with said plunger for moving the same in one direction, resilient means on said armature for regulating its stroke, and resilient means on said plunger for cushioning the stroke of said contacting means and for moving said plunger in the opposite direction.

40 2. In combination, an electromagnet operating on alternating current, a pivoted armature, a plunger, resilient means substantially parallel to the plane, and secured to the rear face and near the pivot, of said armature and adapted to contact with one end of said plunger for moving said plunger in one direction, a second resilient means substantially at right angles to the plane of said armature and secured to the latter near the pivot for causing the first named resilient means to bear against the plunger, and resilient means on said plunger for cushioning the stroke of said contacting means and aiding said retracting means.

55 3. In combination, a frame, an electromagnet, an armature, a striker, a translating device cooperating with said striker, means on the rear face of said armature resiliently cooperating with said striker, the resiliency of said means being greater when said armature is moving toward said magnet than when moving away from said magnet, means on said armature resiliently coating with said frame in moving said armature toward said magnet; and means on said striker resiliently

coating with said frame in moving said armature away from said magnet.

In witness whereof, we have jointly signed the foregoing specification, at New York, in the county and State of New York, this 10th day of December, 1926.

FRANK ALBRIGHT.
